US00D721660S

(12) **United States Design Patent**
Wang

(10) **Patent No.:** **US D721,660 S**
(45) **Date of Patent:** **** Jan. 27, 2015**

(54) **REMOTE CONTROLLER**

(71) Applicant: **iSmart Alarm, Inc.**, Sunnyvale, CA
(US)

(72) Inventor: **Renda Wang**, Tianjin (CN)

(73) Assignee: **iSmart Alarm, Inc.**, Sunnyvale, CA
(US)

(**) Term: **14 Years**

(21) Appl. No.: **29/456,986**

(22) Filed: **Jun. 6, 2013**

(30) **Foreign Application Priority Data**

Dec. 31, 2012 (CN) 2012 3 0664781

(51) **LOC (10) Cl.** **14-03**

(52) **U.S. Cl.**

USPC **D13/168**

(57) **CLAIM**

I claim the ornamental design for a remote controller, as shown and described.

DESCRIPTION

FIG. 1 is a front view of a remote controller showing my new design;

FIG. 2 is a top view thereof;

FIG. 3 is a rear view thereof;

FIG. 4 is a left side view thereof;

FIG. 5 is a right side view thereof;

FIG. 6 is a bottom view thereof; and,

FIG. 7 is a perspective view thereof.

1 Claim, 6 Drawing Sheets

FIG. 1

FIG. 2

FIG. 3

FIG. 4

FIG. 5

FIG. 6

FIG. 7
